SINGLE LEVER LAVATORY SHELL OR THE LIKE

Stephen A. Young, Monticello, Ind.
(Flora, Ind. 46929)

Filed Nov. 30, 1967, Ser. No. 9,602

Term of patent 14 years

Int. Cl. D23—01

U.S. Cl. D23—32

Fig. 1

Fig. 2

Fig. 3

Fig. 4

FIGURE 1 is a top plan view of a single lever lavatory shell or the like embodying my new design.

FIGURE 2 is a front elevation of the same.

FIGURE 3 is a bottom view of the same.

FIGURE 4 is a side elevation of the same.

I claim:

The ornamental design for single lever lavatory shell or the like, substantially as shown.
